UNITED STATES PATENT OFFICE.

ALBERT W. TINKER, OF CLEVELAND, OHIO.

APPARATUS FOR FORMING CONCRETE VAULTS.

Application filed November 13, 1924. Serial No. 749,637.

This invention relates to concrete construction, and is particularly concerned with the formation of reinforced concrete grave vaults. The apparatus shown is for forming the body of a top seal vault and it is to be understood that the method shown may be used for any concrete container or the cover of a bottom seal grave vault as well.

The primary object of the invention is to provide a cheaply made and simple apparatus for forming a substantially rectangular open container of concrete. The apparatus is in the nature of a mould made in separate sections which may be easily assembled before pouring the concrete with a minimum amount of labor and as easily removed from the finished product.

Another object is to provide fastening means to secure the various parts of a mould together, which may be quickly operated and which not only secures the parts together, but in so doing brings the various abutting edges of separate members together by a camming action to eliminate so called fins on the finished product.

Further features and objects of my invention will become apparent in the further description which relates to the accompanying drawings. The essential novel characteristics will be summarized in the claims.

In the drawings Fig. 1 is a perspective of the assembled mold; Fig. 2 is a cross section therethrough as indicated by the lines 2—2 on Fig. 1; Fig. 3 is the transverse cross-section as indicated by the line 3—3 on Fig. 1; Fig. 4 is a fragmentary detail of a corner of one of the molds at the separating point of a pair of mold members; Fig. 5 is a fragmentary cross-section through the corner members of both the inner and outer molds as indicated by the lines 5—5 on Fig. 4; Fig. 6 is a cross-section (similar to Fig. 5) of a portion of the outside molds showing the manner of clamping and securing the separate mold members together.

My apparatus consists generally of an inner member having side and end walls and a roof portion which may be easily and accurately positioned upon a pouring base or slab. The roof portion thereof which I show is made in two or more sections which are simply placed on the assembled side and end walls prior to pouring the concrete. The outer mold members consist of separately removable side and end walls, also positioned by the base, the height of the walls being

greater than those of the corresponding inner mold by substantially the desired thickness of the bottom of the receptacle to be formed. I prefer to make the concrete receptacle upside down whereby the inner mold members may be assembled as an inverted box and whereby the whole area of the bottom is to be utilized as a pouring opening. To remove the mold members, I invert the vault or container together with the mold, preferably by means of trunnions mounted on the exterior mold and while elevated transport the mold to its proper storage space by a trackway and hoist, and remove the various mold members, leaving the vault right side up.

Referring in detail to the drawings and indicating the various parts by numerals, 1 denotes generally the inside mold and 2 the outside mold. The inside mold has preferably separate end walls 5 and 6 and side walls 7 and 8 suitably fastened together and a closure member or temporary roof portion 9 which is preferably made in two sections 10 and 11.

The end members 5 and 6 comprise substantially flat plates 15 suitably reinforced as by structural members such as the angles 17. The upper one of these angle members serves to support the roof members 10 and 11. The side members 7 and 8 are similarly constructed, the plate forming the mold surface being shown as reinforced by angle members 19, the upper one of which supports the edges of the roof members. The intermediate angle members 19 on either side are shown as perforated and subtended by hooked bars 20 which serve to prevent the weight of the concrete poured into the space between the outer and inner mold members from bulging the plate inwardly. The weight of these bars serves to hold them in place while pouring the concrete and later to remove them when the completed vault is overturned as will be later described. The members forming the outer mold are similarly constructed except that the corresponding reinforcing angles are designated 21 for the end members 22 and 23, and 25 for the side plates 26.

The vertical margins of the plates 6 and 7, 23 and 26 carry heavy attaching plates or angles as shown in Figs. 4 and 5, wherein the plate 23 is provided with an angle member 27, while the plate 26 is provided with an abutting member or plate 28 surmounted by a perforated plate 29 shown in elevation

in Fig. 2. The angle member 27 is provided with rigidly attached studs 30 which may be welded or pinned in place and which are adapted to enter elongated perforations 31 in the member 29. The perforations 31 are elongated to facilitate assembly and each has an outwardly facing conical surface at one end thereof indicated at 33. The studs 30 are adapted to receive wing nuts 35, the nut portion of which terminates in a conical surface 36 substantially corresponding to the angle formed by the conical surface of the opening 33. Referring to Fig. 6 it will be seen that by screwing down the wing nuts 10 onto the studs the members 29 and 27 are brought together so that the inner surfaces of the plate 7 and the angle member are forcibly brought into and secured in abutting engagement whereby none of the concrete 15 poured in the mold will tend to form a fin at this point. Such a fin is very undesirable in that it is very likely to prevent the easy removal of the mold members after the concrete is set. Another advantage of the construction of the securing means is that the life thereof is considerably prolonged, even 20 a great amount of wear on the conical surfaces being immaterial.

The inner mold members 6 and 7 are similarly joined by angles 27^a and plate members 28^a and 29^a, an outer surface of the angle 27^a being of course the molding surface and which is therefor provided with a slight draft as contrasted with the inner surface of the angle members 27^a. As shown in Fig. 2 the inner corners of the angle members 27 are provided with inserts 37 which terminate at their upper and lower ends in beveled surfaces 38. The purpose of these inserts is to provide a partially beveled off corner to the vault to be formed whereby the necessity for handles on the vault is obviated. The manner in which these beveled-off corners serve to facilitate handling the vault is set forth in my copending application, Serial No. 749,636, filed November 13, 1924.

Preparatory to setting up the mold members, a block or molding slab designated 40 and shown in Figs. 2 and 3 is carefully cleaned of any accumulated fragments of concrete or other foreign matter. In setting up the mold the end walls 5 and 6 are first placed against the inner line of ribs 41, being 45 retained in upright position by the flanges of the angles 27^a. The side wall members are then located by the ribs and swung into place with the studs projecting through the openings 31. The wing nuts 35 are then 50 applied and tightened up as previously described.

At this point I may use this assembled box-like structure to form a substantially continuous reinforcing member resembling a basket to be later described. The entire 55

exterior surface of the inner mold member is then covered with oil to prevent the mold members from adhering to the concrete. The exterior mold members are afterward assembled and oiled in substantially the 70 same manner, the walls being located by the ribs 42.

The rectangular cavity formed by the outer and inner surfaces of the assembled mold members 1 and 2 respectively is then 75 filled with concrete, (the reinforcing member having been previously placed in the cavity), and a substantially flat bottom for the vault to be formed is obtained by brushing off the surplus concrete even with the 80 upper brim of the mold member 2 and smoothing off the surface with a leveling trowel or float.

After the concrete has set the whole mold may be raised by means of trunnions 50 85 supported as shown in Fig. 1 by the end members 22 and 23 and carried to storing position by suitable hoisting mechanism engaging the trunnions. The mold is there 90 overturned and deposited. All the mold members may then be taken off.

The above described apparatus may be effectively used in forming any size and shape of receptacle as well as a rectangular vault and it will be seen that the members forming the vault may be very easily and cheaply made and rapidly put together to form a complete mold and as easily and quickly removed from the finished product. The sequence of operation for assembling 95 molds provides for putting in place the members which will stand of themselves, and hence no auxiliary apparatus may be provided for this purpose nor unnecessary labor needed. In making concrete vaults it is essential that there be no variations in the shape and size of the brim of the vault. The ribs 41 and 42 not only temporarily 100 position in the mold members in the process of assembly but always maintain, in a very simple manner, an identical size of vault 105 brim.

Having thus described my invention, I claim:

1. In a mold, an end section having flanges extending at rigid angles thereto, said flanges being provided with molding surfaces, a side section having molding surfaces arranged to join the molding surfaces of the flange, a member rigid with one of the sections and overlying the other section to guide the said molding surfaces into joining position, a cam surface formed on the overlying member and means rigid with the other member, arranged to cooperate with such cam surface to bring the molding surfaces together with a sliding action and to thereafter clamp the sections rigidly together.

2. In a mold, a pair of mold members

having separate molding surfaces adapted to abut each other to form in effect a single planular surface, said members having overlapping portions, and means connecting said portions and adapted to draw them together and also shift one of them relative to the other to effect the abutting engagement.

3. In a mold, a pair of mold members having separate molding surfaces adapted to abut each other, said members having portions overlapping each other, an opening in one of said portions, a rigid member carried by the other portion and extending through the opening, and cooperating clamping means engaging the rigid member and adapted to force against one side of the opening to bring the mold members forcibly into abutting engagement.

4. A corner construction for separable mold sections comprising members having molding surfaces adapted to abut and having overlapping portions, a stud carried by one of said portions and extending loosely through an opening in the other portion, and means on the stud engaging such other portion for forcing one of the members along the other to effect the abutting engagement.

5. A corner construction for separable mold sections comprising members having molding surfaces adapted to abut, a flange carried by one of the members, an opening in the flange, a stud in the other mold member extending through the opening, and a nut engaging the stud and bearing with a wedging action against one side of the opening to bring the mold members forcibly together with their adjacent edges flush and simultaneously effect the abutting engagement.

6. In a mold, a pair of mold members having separate molding surfaces abutting each other in substantially the same general plane, flanges carried by the mold members, one of said flanges overlying the other, an opening in one of the flanges, a rigid member carried by the other, and extending through the opening, and cooperating clamping means engaging the rigid member and adapted to engage and force against one side of the opening while the opposite side is free from engagement for bringing the mold members together and for securing them in such position.

7. An apparatus for forming concrete receptacles including end and side wall mold members, said members being provided at

their corners with overlying flanges, one of said flanges being provided with a stud and the other with elongated openings for receiving the stud, a conical surface at one side 60 of said opening, and a nut for engaging the stud having a complementary conical surface at the inner end thereof whereby the mold members may be clamped together with the abutting surfaces forcibly joined. 65

8. A pair of mold members for forming concrete receptacles, one having a perpendicularly disposed flange at its edge provided on one of its surfaces with suitable draft to facilitate drawing the member from 70 the hardened concrete, a plate secured to the other mold member adapted to overlie the opposite surface of the angle member, an aperture therein having a conical surface at one side thereof, a stud rigid with the angle 75 member and projecting through the opening and a conical nut engaging the stud and adapted to cam against the conical surface in the plate to force and secure the mold members into abutting relation. 80

9. An apparatus for forming concrete receptacles comprising end and side wall mold members, the end members being provided at their corners with flanges disposed at an angle to the members, said flanges having 85 draft, and each having a surface adapted to abut and become flush with a surface on the adjacent side members, the flanges being provided with rigid members, and the side wall members with openings for receiving the 90 members, securing devices for engaging the rigid members and bearing with a camming action against a portion of the respective walls of the openings to bring the side surfaces into such abutting relation. 95

10. In a mold, a pair of members extending in parallel relation and arranged to join, each of the members having molding surfaces and adjacent surfaces extending at an angle thereto, said adjacent surfaces being adapted to abut, a plate rigid with one of the members and an opening therein, a stud rigid with the other member and extending therethrough, and means carried by the stud adapted to cam against a surface of the 105 opening to shift the abutting surfaces forcibly toward each other and thereafter clamp the plate against a said other mold member.

In testimony whereof, I hereunto affix my signature.

ALBERT W. TINKER.
